(57) **CLAIM**

The ornamental design for a moss pole, as shown and described.

DESCRIPTION

FIG. 1 is a front, left and top perspective view of a moss pole showing my new design;

FIG. 2 is a rear, right and bottom perspective view thereof;

FIG. 3 is a front, right and bottom perspective view thereof;

FIG. 4 is a top view thereof;

FIG. 5 is a bottom view thereof;

FIG. 6 is a right view thereof;

FIG. 7 is a left view thereof;

FIG. 8 is a front view thereof; and,

FIG. 9 is a rear view thereof.

The broken lines illustrate portions of the article that form no part of the claimed design.

1 Claim, 9 Drawing Sheets
